2 SHEETS—SHEET 2.

UNITED STATES PATENT OFFICE.

GEORGE HENRY BISHOP, OF CALGARY, ALBERTA, CANADA.

CATTLE-GUARD.

1,397,752.

Specification of Letters Patent. Patented Nov. 22, 1921.

Application filed January 3, 1921. Serial No. 434,628.

To all whom it may concern:

Be it known that I, GEORGE HENRY BISHOP, a subject of the King of Great Britain, a resident of the city of Calgary, Province of Alberta, Dominion of Canada, have invented certain new and useful Improvements in Cattle-Guards, of which the following is a specification.

This invention relates to improvements 10 in cattle guards, consisting of metal plates applied on the ties cross-wise to the rails, and the objects of the invention are to prevent cattle straying on a railroad track, to provide such a cattle guard that is not liable 15 to go out of repair, and to render the cattle guard simple in construction and capable of effectively performing the functions required of it.

The invention consists essentially of the 20 improved construction of cattle guard particularly described in the following specification, illustrated in the accompanying drawings which form part of the same, and set forth in the appended claims.

25 In the drawing:

Figure 1 is a perspective view of the improved cattle guard.

Fig. 2 is a side view of the same.

Fig. 3 is a perspective view of a slightly 30 altered embodiment of the improved cattle guard.

Fig. 4 is a side view of the same.

Like characters of reference refer to corresponding parts in the several figures.

35 Referring to the drawing; A represents a railroad track and B the improved cattle guard.

The improved cattle guard comprises a central section 10 formed of a plate which 40 is angular in cross section, and is turned upwardly at one end, forming a flange 11 bolted or otherwise fastened to the bottom end of one side of the tie 12.

The plate 10 extends upwardly at an angle 45 from the bottom of the tie 12 to the top of the tie 13 and the end of the said plate 10, remote from the flange 11 is bent downwardly providing a section 14 extending substantially vertically and abutting, as at 15, 50 the top of the tie 13.

Rectangular openings 16 and 17 are cut off from the head of the plate 10 to provide clearance from the rails.

The triangular recess formed underneath 55 the plate 10 by the side wall of the tie 13 may be filled with cement or other suitable

substance, thus affording a supporting means for the plate 10.

The tie 12 located on one side of the section 10 is provided on its top face with a 60 plate 18 of inverted V-shape. The two leg-members of this V-shaped plate 18 are bent outwardly and form the flanges 19 and 20 abutting the top of the tie 12.

The plate 18 may be fastened to the tie 12 65 by means of spikes driven therein through the flanges 19 and 20.

The plate 18 is made of three sections placed, one section on each side, and one 70 between the rails.

The top face of the tie 21 on the opposite side of the section 10 is provided with a similar plate 22 of inverted V-shape and provided with the flanges 23 and 24 abutting the top of the tie 12, and designed to receive the fastening means adapted to retain the plate 22 in proper position.

Like the plate 18, the plate 22 is also made of three sections fastened to the tie 21, one section on each side and one section between the rails, so as to provide clearance therefor.

The depression 25 formed between the ties 13 and 21 may be filled with cement, or other suitable substance, so that when the 85 animals attempt to pass, they will not injure their legs by falling into the depression 25.

This cattle guard will be located at crossings so that should any animal endeavor to 90 stray on the track, they will slip on the plate 18 and on the section 10 and be frightened.

Figs. 3 and 4 illustrate a somewhat modified form of the cattle guard which consists of a section 10^a formed of a plate having 95 one edge provided with a flange 11^a fastened to the bottom of a wall of the tie 12^a and extending upwardly and angularly therefrom, over and past the tie 26. The plate 10^a is bent downwardly at an obtuse angle 100 27, and extends over the tie 28; the said plate 10 is then bent again forming a horizontal section 29 having its end inflexed upwardly, thus providing the flange 30 adapted to receive the fastening means to 105 be driven into the tie 31.

The plate 10^a is suitably fastened to the tie 26 and 28 as at 35 and 36.

A plate 32 extends above the horizontal section 29 of the plate 10^a, downwardly to 110 the top of the tie 31 where the said plate 32 is bent to a flange 33 abutting thereto,

A reinforcing angular member 34 may be fastened to the said plate 32 and on top of the tie 31 so as to enable the plate to support any additional weight that may be placed 5 thereon as when an animal would step on the plate.

A plate 37 extends downwardly over and past the tie 31, to which it is fastened, and is bent as at 38, affording a horizontal section having an end inflected upwardly and forming a flange 39 fastened to the tie 40.

The plate 37 is also bolted to the angular brace 34 supported by the tie 31.

Above the horizontal section formed by 15 the bend 38 of the plate 37, another plate 42 extends downwardly to the top of the tie 40. The plate 42 is bent horizontally to a flange, then upwardly and again downwardly providing a V-shaped section 43 abutting the 20 top of the tie 40.

An angular brace 44 to which the plate 42 is bolted, together with the upwardly extending portion of the V-shaped section 43 serves to reinforce the same.

25 The tie 12^a is provided on the top thereof with a plate of inverted V-shape 18^a flanged and fastened thereto, exactly as that provided on top the tie 12 in Fig. 1, and described above.

30 The plates 18^a, 10^a, 32, 37 and 42 are all channelled to provide clearance for the rails A.

The slanted plates reinforced by members 34 and 44 as described above are also held 35 in their slanting position by the horizontally extending rods 45 and 46.

The recesses formed underneath the plate 10^a and 37, between the ties 26, 28, 31 and 40 may be filled with cement or other suitable 40 material, as illustrated in Figs. 3 and 4.

The construction of the cattle guard is of an extremely simple nature and could be advantageously utilized in many places where other forms of cattle guards would prove 45 defective.

As many changes could be made in the

above construction and many widely different embodiments of my invention within the scope of the claims constructed without departing from the spirit or scope thereof, it 50 is intended that all matter contained in the accompanying specification and drawings shall be interpreted as illustrative and not in a limiting sense.

What I claim as my invention is:

1. A railway cattle guard comprising a main section consisting of an apertured plate adapted to form two sides of an obtuse triangle formed with a flange at one end and horizontally extended at the other end, a 60 flange on said horizontal extension, a plurality of inclined guard plates formed integral with and overlapping said apertured plate, and additional inclined guard plates arranged parallel with said first guard plates 65 and connected thereto by means of a reinforcing element.

2. In a cattle guard the combination with the railway ties of a main apertured and angularly bent plate section adapted to fit 70 over two of the said ties and between the second and third tie and a plurality of smaller angularly bent and flanged plates provided with reinforcing means and adapted to be secured on the ties and to overlap in 75 turn said main plate and one another, securing means for said main plate.

3. A railway cattle guard comprising a main section composed of an apertured plate adapted to form two sides of an obtuse triangle formed with a flange at one end and being horizontally extended at the other end, a pair of flanged plates of inverted V-shape 80 supported on ties on opposite sides of said main section.

In witness whereof I have hereunto set my hand in the presence of two witnesses.

GEORGE HENRY BISHOP.

Witnesses:

THOMAS M. TURRDIS,
IRENE KIRWAN.
